UNITED STATES PATENT OFFICE.

BENJAMIN RATCLIFFE ADKINS, OF UPPER WARLINGHAM, AND WILLIAM YORATH LEWIS, OF SOUTHEND-ON-SEA, ENGLAND.

MEANS FOR SUPPORTING SHAFTING.

Application filed November 5, 1923. Serial No. 672,979.

To all whom it may concern:

Be it known that we, BENJAMIN RATCLIFFE ADKINS and WILLIAM YORATH LEWIS, both subjects of the King of England, and 5 residing, respectively, at Upper Warlingham, Surrey, in England, and Southend-on-Sea, Essex, in England, have invented certain new and useful Improvements in Means for Supporting Shafting, of which the following is a specification.

This invention relates to means for supporting shafting and is more especially applicable to a bearing support for the adjacent ends of sections of the shafting of a 15 conveying apparatus. To save expense it is desirable to keep the supporting bearings as far apart as is practicable, and the main object of the present invention is to provide a bearing support of such construction as 20 to facilitate the erection and handling of the shafting and to avoid severe strains on the shafting and its bearings caused for instance by the sagging of the shafting between its supports.

According to the present invention a stub shaft supported in suitable bearings is connected to the main shafting by means of a 25 flexible diaphragm. When two adjacent ends of sections of the shafting are to be supported, a flexible diaphragm may be employed to connect one or both of the sections to a stub shaft supported in bearings 30 which are preferably of the self-aligning type. Such an arrangement makes allowance for changes or inaccuracies in the 35 alignment of the shafting, and prevents the shafting or its bearings from being subjected to excessive strains from any cause.

It may be necessary in some cases to arrange 40 the supporting means in such a manner as to allow for the longitudinal expansion of the shafting. This may conveniently be effected by surrounding one end of the stub shaft by a sleeve which is connected to the main shafting by means of 45 the flexible diaphragm the stub shaft and the sleeve being connected together by means of a key and keyway so that the main shafting and the stub shaft will rotate in synchronization with one another but will be free

to move longitudinally relative to one another.

The invention is more especially applicable to conveying apparatus in which cars or other bodies are impelled along a track 55 by means of a continuously rotating screw thread, and may be employed to provide a bearing support for the adjacent ends of sections of the shafting on which the screw thread is carried. When the rail track is 60 straight and it is only necessary to allow for the sagging of the shafting between its bearing supports and for inaccuracies in laying, it will generally be sufficient to connect the stub shaft rigidly to one section 65 of shafting and to provide a flexible diaphragm for the connection to the other section, self-aligning bearings being employed for the stub shaft.

When, however, the two sections of shafting 70 are out of alignment owing to curving of the rail track or a change in gradient, it is necessary to provide means whereby the rotation of one section of shafting may be synchronously transmitted to the other section. This may conveniently be effected by 75 providing two stub shafts, each of which is connected by means of a flexible diaphragm to one of the sections of the main shafting, these stub shafts being mounted in suitable 80 bearings and connected together by means of bevel or other gearing.

The invention may be carried into practice in various ways, but the accompanying drawings illustrate by way of example two 85 preferred constructions in which the invention is applied to screw conveying apparatus. In these drawings—

Figures 1, 2 and 3 show a construction 90 for use when the two sections of shafting carrying the screw thread are in line with one another, these figures respectively being a vertical section through the axis of the shafting, a transverse section and a plan, and

Figure 4 shows in horizontal section another construction applied to the case when the track is curved so that the two sections of shafting are not in alignment with one another.

In the construction shown in Figures 1-3, the screw thread A is carried by means of posts A' or the like on tubular shafting, the adjacent ends of two sections B and C of this shafting being shown in the drawings. The end of one section B of the shafting is closed by means of an end plug D having a central opening, in which is disposed one end of a sleeve E held to the 10 end plug D by means of a key pin E'. The other end of the sleeve E is screwthreaded on its inner surface for the reception of a stub shaft J, a tapered pin K being provided to secure the stub shaft to the sleeve 15 E when it has been screwed into position therein. This stub shaft J is mounted in bearings F of the self-aligning type. The casing containing these bearings is divided into two parts, the upper part G being detachably secured by means of bolts G' to the lower part G² which is formed integral with the bearing pedestal H. This pedestal H is provided with curved slots or grooves H' H² through which the overlapping ends of the screw thread A pass as they rotate. The stub shaft J carries at its further end a boss L which is connected by means of a diaphragm M to an end plug N in the other section C of the main 20 shafting. The diaphragm M is secured to the end plug N by means of a ring O provided with webs O' which extend near to the boss L so as to limit relative transverse motion between the stub shaft J and the end plug N. Ribs N' are also provided on the end plug N in a position adjacent to shoulders L' on the boss L, these ribs N' serving to limit relative longitudinal motion between the stub shaft J and the end 25 plug N. The ribs N' and the webs O' thus serve to prevent excessive strains from being put on the diaphragm M, for example when handling or laying sections of the main shafting. To allow for the expansion and contraction of the shafting, without straining the diaphragms, it may be necessary to provide means whereby the shafting can freely move longitudinally relative to the stub shaft. This may be 30 effected in a simple manner, as shown, by providing a keyway in the boss L, in which a key J' mounted on the shaft J engages. This arrangement permits the necessary longitudinal movement but does not allow any relative rotational movement. Alternatively, this longitudinal movement may be provided for by corrugating the diaphragm concentrically or in certain instances, the plain diaphragm without corrugations may 35 be sufficient to give all the necessary longitudinal movement caused by the expansion and contraction of the shafting, and in this case the provision of a key and keyway or like device becomes unnecessary.

When it is desired to remove one section 65 of the shafting for repairs, the upper part G of the casing and the pins K and E' are removed. The sleeve E is then unscrewed from the stub shaft J until it is clear of the end of the shaft. A similar operation 70 is carried out at the other end of the section concerned, which is then free to be lifted out.

In the case when the two sections of the shafting are out of alignment, for instance 75 when the track is curving or the gradient is changing, a modified construction will generally be required.

Such a construction is illustrated in Figure 4 for the case when the track is curving. It will be understood that a similar construction may be employed for a change of gradient, the sole difference lying in the angular position of the other parts of the device relative to the bearing pedestal. In this construction the adjacent ends of the two sections P P' of the shafting are each closed by an end plug Q, to which a diaphragm R is secured by means of a ring S, the other end of the diaphragm being fixed to a boss R'. As in the previous construction the ring S carries a web S' extending near the boss R' and the end plug Q is provided with ribs Q', to prevent excessive movements which would injure the diaphragm. Within each boss R' is mounted a stub shaft T. The two stub shafts are similar to one another, except that one of them is connected to its boss R' by means of a key T' and a keyway whilst the other connection is formed by a pin T², since it is only necessary to provide a keyed connection at one end of a section of shafting. Each stub shaft T carries at its inner end a bevel wheel U and is mounted in compound ball bearings V V', the ball races being held in position by means of a nut W screwed on the shaft. The bearings V V' are enclosed in a casing X having a central enlargement X' within which the bevel wheels U engage with one another. The bearings V V', the stub shaft T and the bevel wheel U are held in the casing X by means of a small ring X² in such a position that the teeth of the bevel wheels 110 are in engagement with one another. The casing X is divided into two parts bolted together, the upper part not being shown in the drawing since it lies wholly above the plane of the section. The lower part 115 is formed integral with the bearing pedestal Y which is similar to that shown in Figures 1-3.

The provision of a diaphragm at the end of each section of the main shafting is necessary 120 in order to take up the strain of any malalignment between a section and its stub shaft and also to take up the strain which

would otherwise be imparted to the stub shaft by reason of the sagging of the shafting between supports. By this means the two stub shafts may be firmly held within 5 the compound bearings to keep the teeth of the bevel wheels properly in mesh without any overstraining of the parts.

To remove either of the sections P or P' of the shafting, the upper part of the 10 bearing casing X is removed, and the two rings X² are lifted out of position. The stub shafts T, the bearings V V' and the bevel wheels U can then be moved longitudinally until the ends of the stub shafts 15 come up against the end plugs Q. This movement is sufficient to bring the teeth of the bevel wheels U out of engagement with one another, and when a similar operation has been carried out at the other end of 20 either of the sections P or P', that section of shafting can be lifted out. In the event, however, of the other end of the section P or P', which it is required to remove, being carried in a bearing of the type illustrated 25 in Figures 1-3, it will of course be necessary to release it by unscrewing the sleeve E in the manner previously described.

It will be understood that the particular constructions have been described by way 30 of example only and that the details of the invention may be modified in various ways to suit requirements without departing from the scope of the invention.

What we claim as our invention and desire 35 to secure by Letters Patent is:

1. In means for supporting shafting, the combination of a length of the shafting, a stub shaft, bearings in which the stub shaft is supported, and a flexible diaphragm by 40 means of which the stub shaft is connected to the main shafting as set forth.

2. In means for supporting shafting, the combination of two adjacent sections of shafting, a stub shaft, bearings in which the 45 stub shaft is supported, a flexible diaphragm by means of which the stub shaft is connected to one section of the main shafting, and means whereby the stub shaft is connected to the other section of the shafting as 50 set forth.

3. In means for supporting shafting, the combination of a length of the shafting, a stub shaft, bearings in which the stub shaft is supported, a sleeve surrounding the stub 55 shaft, a flexible diaphragm by means of which the sleeve is connected to the main shafting and means whereby the sleeve and the stub shaft are connected together so that there can be no relative rotation between them as set forth.

4. In means for supporting shafting, the combination of two adjacent sections of shafting, a stub shaft, bearings in which the stub shaft is supported, a sleeve sur-

rounding part of the stub shaft, a flexible 65 diaphragm by means of which the sleeve is connected to one section of the main shafting, a keyed connection between the sleeve and the stub shaft, and means whereby the stub shaft is connected to the other section 70 of the main shafting as set forth.

5. In means for supporting shafting, the combination of two adjacent sections of the shafting, two stub shafts, bearings in which the stub shafts are supported, two flexible diaphragms by means of which the two stub shafts are respectively connected to the two sections of the main shafting, and means for connecting the two stub shafts together as set forth. 80

6. In means for supporting shafting, the combination of two adjacent sections of the main shafting the axes of which are out of alignment with one another, two stub shafts, bearings in which the stub shafts are supported, a sleeve surrounding each stub shaft, two flexible diaphragms by means of which the two sleeves are respectively connected to the two sections of the main shafting, means whereby each sleeve is connected to its stub shaft so as to rotate therewith, and bevel gearing by means of which the stub shafts are connected together as set forth. 90

7. In conveying apparatus of the type in which bodies are impelled along a track by means of a continuously rotating screwthread, the combination of the screwthread, two adjacent sections of shafting on which the screwthread is carried, a stub shaft, bearings in which the stub shaft is supported, a flexible diaphragm by means of which the stub shaft is connected to one section of the shafting, and means whereby the stub shaft is connected to the other section of the shafting such that the two sections 100 of shafting will rotate in exact synchronism with one another as set forth. 95

8. In conveying apparatus of the type in which bodies are impelled along a track by means of a continuously rotating screwthread, the combination of the screwthread, two adjacent sections of shafting on which the screwthread is carried, two stub shafts, bearings in which the stub shafts are supported, two flexible diaphragms by means 110 of which the two stub shafts are respectively connected to the two sections of the main shafting, and means for connecting the two stub shafts together as set forth. 115

9. In conveying apparatus of the type in which bodies are impelled along a track by means of a continuously rotating screwthread, the combination of the screwthread, two adjacent sections of shafting on which the screwthread is carried the axes of the 120 two sections being out of alignment with one another, two stub shafts, bearings in which the stub shafts are supported, a sleeve

surrounding each stub shaft, two flexible bevel wheels engage with one another and 10
diaphragms by means of which the two cause the two sections of the main shafting
sleeves are respectively connected to the two to rotate in exact synchronism with one an-
sections of the main shafting, a keyed con- other as set forth.
5 nection between one sleeve and its stub shaft, a rigid connection between the other sleeve and its stub shaft, and a bevel wheel mounted on the end of each stub shaft in such a manner that the teeth of the two

In testimony whereof we have signed our names to this specification.

BENJAMIN RATCLIFFE ADKINS.
